UNITED STATES PATENT OFFICE.

WILLIAM A. MCCALLUM, OF CINCINNATI, OHIO.

DESIGN FOR A FEEDER-ARM FOR POLES OF ELECTRIC RAILWAYS.

SPECIFICATION forming part of Design No. 35,424, dated December 10, 1901.

Application filed November 1, 1901. Serial No. 80,829. Term of patent 14 years.

To all whom it may concern:

Be it known that I, WILLIAM A. MCCALLUM, a citizen of the United States, residing at Cincinnati, in the county of Hamilton and State of Ohio, (post-office address 431 and 433 East Front street, Cincinnati, Ohio,) have invented and produced a new, useful, and original Design for Feeder-Arms for Poles of Electric Railways, of which the following is a specification.

My invention relates to a design for "feeder-arms" for the "poles" or posts used in electric-railway construction—that is to say, the cross-arms attached to the poles and constituting the supports for the feed wires or conductors; and it consists of a new, useful, and original design for the same as an article of manufacture.

My invention is illustrated in the accompanying drawing, forming part of this specification, and in which the figure is a general perspective side elevation.

As shown in the drawing, the design consists of a web A, disposed in a vertical plane of limited depth, but extended horizontally to the extreme length of the arm and bifurcated to inclose a cylindrical central opening b and one or more similar openings c of smaller diameter disposed at each side of the central opening b at about relatively equal distances apart, the outer ones being at the extremities of the arm. The vertical web is of somewhat increased depth at the walls of the central opening and diminishes thence toward the opposite extremities. The entire arm is divided into two parts on diagonal vertical

planes through the walls of the central opening b, each part overlapping tangentially at the division planes and united by bolts passing through the overlapping portions, 40 whereby the walls of the central opening form a circular clamp embracing the trolley-pole, and thus supporting the arm thereon. The upper and lower edges of the web A are laterally extended into horizontal flanges d, extending outward uniformly at either side, but widening in long curves to meet the rotundity of the central opening, around which the flanges circle in a narrower "head." The horizontal flange lies against the cylindrical 50 walls of the smaller openings, which walls are extended vertically slightly above and below the normal width of the main web A and are finished with narrow marginal flanges or beads e. The lateral flanges here referred to 55 are in effect beadings at the edges of the web, which add lateral strength to the arm and also give a pleasing appearance to the structure. The smaller cylindrical openings contain the insulating posts or pegs to which the 60 conducting-wires are attached.

I claim as my invention, and desire to secure by Letters Patent of the United States—

The design for a feeder-arm for poles of electric railways as herein shown and described. 65

In testimony whereof I have hereunto set my hand in presence of two subscribing witnesses.

WILLIAM A. MCCALLUM.
